AUDIBLE SIGNALING HANDLE

Joseph Ford, Trenton, N. J.

Application August 3, 1936, Serial No. 94,097

3 Claims. (Cl. 46—175)

This invention relates to an audible signaling handle for portable drinking vessels, and has for its object to provide, in a manner as hereinafter set forth, a handle of such class so constructed whereby the user of the vessel may readily attract the attention of an attendant when occasion requires.

A further object of the invention is to provide, in a manner as hereinafter set forth, a handle designed primarily for use in connection with drinking vessels and with the handle including an upstanding hand gripping part so constructed to enable the user of the vessel to conveniently signal an attendant for the purpose of having the vessel replenished or for any other reason desired.

A further object of the invention is to provide, in a manner as hereinafter set forth, a handle for drinking vessels having arranged therein, the components of an audible signal enabling the user of the vessel to conveniently signal to direct the attention of an attendant or a waiter.

Further objects of the invention are to provide, in a manner as hereinafter set forth, an audible signaling handle for drinking vessels which is simple in its construction and arrangement, strong, durable, compact thoroughly efficient in use, readily set up, not marring the appearance of the vessel, and inexpensive to manufacture.

To the above ends essentially the invention consists of such parts and such combination of parts which fall within the scope of the invention as claimed.

The adaptation of the invention is shown, by way of example, as extended laterally from and integral with the container portion of a mug.

In the accompanying drawing:—

Figure 1 is a vertical section through a mug embodying one form of the invention.

Figure 2 is a fragmentary top plan thereof.

Figure 3 is a fragmentary perspective view of the handle.

Figure 4 is a fragmentary vertical section embodying a modified form of the invention.

Figure 5 is a perspective detailed view of an insert used in connection with the form shown in Figure 4.

Figure 6 is a view similar to Figure 4 showing a further modified form of the invention, and

Figure 7 is an enlarged fragmentary section showing the construction of the insert employed in the form shown in Figure 6.

Referring to the drawing in detail, the numeral 1 indicates the open top container part of a mug or the like. Integral with the container part as well as arranged in laterally disposed re-

lation thereto is the handle 2 in accordance with this invention. The handle 2 comprises a one-piece body formed of an outer straight vertical portion 3 and a pair of spaced parallel horizontally disposed top and bottom portions 3^a, 3^b respectively angularly disposed with respect to and having their outer ends merging into the upper and lower ends of the portion 3. The inner ends of the portions 3^a, 3^b merge into the outer periphery of the container part. The latter may be of any desired shape, and preferably will be cast or moulded from glass, porcelain, metal or the like. The handle preferably will be of the same material as body 1.

Opening through the upper end of the vertical portion 3 of the handle is a short bore 4 having the wall 5 thereof extending in parallel relation to the outer face of the portion 3 of the handle. The remaining wall portion of the bore 4, indicated at 6, is curved and downwardly tapering. The wall 6 merges into the wall portion 6 which co-operates with the wall 5 to provide a restriction 7 opening through a shoulder 8 which forms the upper wall of an opening 9 in the outer face of the portion 3. The opening 9 is provided with an inwardly and upwardly inclined bottom wall 10 which is substantially in alignment with the rear edge of the restriction 7. The shoulder 8 extends across the restriction 7 and terminates between the restriction and the inner face of the handle portion 3. Extending from the shoulder 8 to the bottom of the handle portion 3 is a cylindrical bore 11 having its front wall in alignment with the wall 5 of the bore 4. At the point of emergence between the bore 11 and opening 9 a pointed projection 12 is formed which is located beneath the restriction 7 and provides an obstruction for air which is forced into the bore 4 and through the restriction.

In the form shown in Figure 4 the straight portion 13 of the handle is provided with a cylindrical bore 14 extending throughout the length of such portion and opening through the top and bottom thereof. Preferably a lip 15 is provided in encircling relation to the upper end 40 of the bore 14. The outer face of the portion 13 is provided with an opening 16 similar to the opening 9 heretofore described. Adapted to be inserted into the bore 14 so that its lower face is substantially flush with the upper wall of the opening 16 is an insert 17 which is substantially cylindrical in form with one face 18 cut away to provide a restricted passage 19 adjacent the opening 16. The bore 14 and opening 16 form a pointed projection 20 similar to the projection 55

12 heretofore described, which is located directly beneath the restricted passage 19 and provides an obstruction for air which is forced into the bore 15 and through the passage 19.

- 5 In the form of the invention shown in Figure 6 the straight handle portion 21 is provided with a cylindrical bore 22 opening through the lower face of the portion 21 and terminating in spaced relation to the upper face of the handle portion. 10 Opening through the upper face of the portion 21 is a downwardly tapered bore 23 which provides a restricted opening 24 into the upper end of the bore 22, circumferentially of the restricted opening 24 15 provides a shoulder 25 disposed transversely of the handle portion 21. Adapted to be inserted into the bore 22 so as to abut against the shoulder 25 is an insert 26 which provides an obstruction to air which enters through the bore 23 and 20 passes through the restricted opening 24.

The insert 26 preferably will be substantially in the form of an inverted cup 27 having mounted therein a rotatable element 28 comprising a plurality of vanes which is mounted to rotate in a 25 transverse plane with respect to the handle portion. Disposed beneath the rotatable element 28 is a rotatable element 29 formed with spaced convex top and bottom walls and having opposite edge portions thereof mounted in sockets 30 30 formed in the member 27 to rotate in a longitudinal plane with respect to the handle portion. Preferably a lip 31 will be provided at the top of the handle portion 21 which is similar to the lip 15 heretofore described.

- 35 In the use of a mug handle embodying this invention, air is forced into the bores 4, 14 or 23, such as by placing the lips around the upper ends of the bores and blowing therein. Due to the restrictions in spaced relation to the upper 40 ends of such bores, and to the obstructions disposed beneath the restrictions, a whistling noise results from the passage of the air from the restriction.

If desired an insert such as 26 may be employed 45 in lieu of the insert 17, and in such use the opening 16 may be temporarily closed in any suitable

manner such as by placing the finger thereover. In like manner the insert 26 may be inserted into the bore 11 and employed in connection with the handle shown in Figure 1. When the insert 26 is so used, the opening 9 preferably will be temporarily closed in the same manner as suggested for the closing of the opening 16.

The portions 3, 13, 20 constitute hand-grip parts. The portions 3^a, 3^b constitute combined attaching and spaced parts and are employed 10 for spacedly connecting a hand-grip part to a receptacle, such by way of example as the body of a mug as shown.

The forms of the invention herein illustrated and described are intended to portray practical 15 embodiments thereof, and it is to be understood that changes and variations may be made which fall within the scope of the invention as claimed.

What I claim is:—

1. A whistle drinking mug comprising a liquid 20 holding body, a hollow tubular whistle adapted to make an audible signal upon the introduction of a blast of air into the hollow tube, and means holding said whistle in spaced relation to said liquid holding body whereby said whistle provides 25 a grip handle for the mug.

2. A whistle drinking mug comprising a liquid 30 holding body, a hollow tubular whistle adapted to make an audible signal upon the introduction of a blast of air into the hollow tube, means holding said whistle in spaced relation to said liquid holding body whereby said whistle provides a grip handle for the mug, and a portion of said whistle and a portion of said spacing means combinedly forming a mouth piece for said whistle. 35

3. A whistle grip handle for receptacles comprising a hollow tubular whistle stem, means cooperating with said stem to provide an audible signal upon the introduction of a blast of fluid 40 into said stem, means for spacedly securing the whistle stem to a receptacle whereby to provide a grip handle for the receptacle, and a portion of said stem and of said last named means combinedly forming a mouth piece for the whistle. 45

JOSEPH FORD.
